CHARLES J. SHEPARD, OF BROOKLYN, NEW YORK.

Letters Patent No. 72,095, dated December 10, 1867.

TUBULAR HEATER.

The Schedule referred to in these Letters Patent and making part of the same.

TO ALL WHOM IT MAY CONCERN:

Be it known that I, CHARLES J. SHEPARD, of Brooklyn, Kings county, New York, have invented, made, and applied to use certain new and useful Improvements in the Construction of Tubular Heaters for Heating Air or Water; and I do declare the following to be a full, clear, and correct description of the same, reference being had to the accompanying drawings, making part of this specification, and to the letters of reference marked thereon, in which—

Figure 1 is a sectional side elevation of my improved tubular heater.

Figure 2, an end view of the front of the same.

Figure 3, a top view of the grate-plate, slide-valve rests, and a part of the air-heating chamber.

Figure 4, a rear view of combustion-chamber and flue.

Figure 5, a plan view of the same.

Figure 6, a view of division-plate sometimes employed by me.

In the drawings, like parts of the invention are indicated by the same letters of reference.

The nature of the present invention consists—

(a.) In combination with the grate E, ash-pit D, and combustion-chamber C, the slide-valve I.

(b.) In the use or employment of a slide-valve at the junction of the upper and under front flues, for the purpose of providing a direct draught to the chimney and the removal of ashes from the upper flue.

(c.) In the use or employment of the upper front flue, covered externally with a non-conducting lining, as a portion of the combustion-chamber.

(d.) In the use or employment of the back flue, and the door or doors connected therewith, for the purpose of affording ready access to the tubes for cleaning the same and for cleaning the flue at the same time.

(e.) In the use or employment of a corrugated tubular internally-flanged chamber, provided with an incombustible termination, by the employment of which the oxygen is more completely prepared by its exposure, as more fully described.

(f.) In the use or employment of a semi-cylindrical reverberating chamber of combustion in combination with a flue and a series of tubes, which chamber of combustion is provided with a non-conducting reverberating arch, by means of which the gases are kept highly heated in their passage, are commingled, concentrated, and consumed prior to their passage to the tubes.

(g.) In the use or employment of a feeding-chamber, in combination with an arched chamber of combustion and the abutments for properly distributing the fuel upon the grate.

(h.) In constructing the bed-plate or grate-plate in such a manner that the same shall form a support for the grate and brick-work of the chamber of combustion, as well as the bed of the front flue.

(i.) In the use or employment, in combination with a series of tubes, of a division-plate, 27, for the purpose hereinafter described.

To enable those skilled in the arts to make and use my invention, I will proceed to describe the construction and operation of the same.

A and A² show any number of tubes held in or connected with the circular plates a, provided with the flanges, recesses, or collars b, which flanges, recesses, or collars project beyond the ends of the tubes, or, if cast tubes are used, may be merely holes in the plate, through which the tubes may pass, abutting against a flange on the outside of the tubes, or by any other mechanical construction. B is a cylindrical casing in which are placed the combustion-chamber C, ash-pit D, grate E, supported by the grate-plate E², and air-chamber F, to supply fresh oxygen to the burning fuel. This air-chamber F is made up of two plates, forming, when put together, a series of air-spaces marked c, in figs. 4 and 5 of the drawings. These air-spaces c are closed at the top, and the air entering them leaves them through the openings 21, as clearly shown in fig. 2. The backs of these air-spaces form a series of cylinders or corrugations, as clearly shown in fig. 5, provided with flanges projecting into the interior of the air-spaces, and dividing each air-space into two parts; these flanges forming additional surfaces for heating the air in its passage through the same. H shows the upper front flue, and G the lower front flue of the heater. The air-chamber F forms the front wall of the upper front flue H, while the lower front flue G is divided from the ash-pit D by the plate 28. Within this cylindrical casing are also con-

tained the front slide or other valve I, and the rear slide or other valve J. Upon one side of this casing is the opening K for the exit of the smoke; or, if desired, a division may be placed in the back flue N, by which the current arising from combustion may be changed and taken from the back flue. At the top of this cylinder-casing can be placed a feed-chamber, L, which feed-chamber may be either inclined or perpendicular, which feed-chamber is intended to supply fuel to the grate E. The chamber of combustion is lined upon its exposed surfaces with any non-conducting material, 29, the effect of which is to cause the same to act as a reverberating chamber, throwing back upon the fire the heat thrown out from the same, and causing a more perfect combustion of the gases evolved in combustion. The upper flue is also lined with a non-combustible material, 29, and forms a portion of this reverberating chamber. M is the shell of the back flue or flues N, through which an exit for the smoke can be made when desired by a division in the flue N. This shell is provided with a door or doors, O, thus giving free and immediate access to the tubes A and A² and flue N, for the purposes of examination and cleaning the same. P² is the front shell of the cylindrical casing B, the rear portion of which forms the front section of the combustion-chamber. Attached to the front of this shell is the door-frame P for supporting the doors Q, giving access to the combustion-chamber and ash-pit, as also the door R giving access to the feeding or supply-chamber L. S is a jacket for enclosing the whole furnace, which jacket may be provided with suitable inlets and outlets for the admission and exit of air when no brick-work is used in setting the furnace in position.

My improved tubular heater being thus constructed, the operation may be thus described: The fuel is fed through the feed-doors to the grate, and there ignited. The heated gases arising from the fire proceed to the point d, but before reaching that point, are met at the point shown by the arrow by a current of fresh oxygen passing through the tubular chamber F, to which tubular chamber said current of oxygen is admitted from the ash-pit D, at the point shown by the arrow, through openings e in the bed or grate-plate E². At the point of the combustion-chamber where the fresh oxygen enters, as just described, are incombustible openings 30. The oxygen thus admitted, and the highly-heated gases, are concentrated and commingled at this point, consumed, and pass into the front flue H, whence they are supplied to the pipes A, and, having passed through these tubes, connect with the upper flue, take the course indicated by the arrows, and thence into the back flue N, returning through the lower tubes A² into the flue G, and out of the opening K. The front slide-valve is reached from the open fire-door Q, and is placed between the grate E and fire-door Q, and is employed to admit of the removal of clinkers, ashes, or coal from the grate, and also to admit oxygen when desired at that portion of the furnace, through a slot made by the withdrawal of the valve I; or the overlap of the valve may be provided with a series of openings for that purpose. The slide-valve J provides for a direct draught to the chimney, and the movement of the valve for that purpose clears the flue H of any ashes by dropping the same into flue G. The corrugated tubular chamber, flanged upon its interior, and having an incombustible termination, more completely prepares the oxygen admitted thereto, by exposing it to the action of the intense heat of the upper front flue, and this chamber, with its large internal surface, as the air traverses the numerous tubular channels composing it, and is concentrated for contact with the heated gases of the fuel. An intense combustion of the gases is secured at the junction of the upper front flue and the chamber of combustion. The semi-cylindrical reverberating chamber of combustion, provided as it is with a non-conducting arch, tends to keep the gases highly heated in their passage through the same, and commingles and concentrates them prior to their entrance into the tubes. This produces a most complete combustion and an increased usefulness in their after passage through the tubes. The admitted heated oxygen, the concentration, the increased temperature arising from the non-conducting walls, all tend to produce a great economy and utility in a great degree. The bed-plate or grate-plate (see fig. 4) extends the entire length and width of the chamber of combustion and the flues, and is so constructed that it forms a support not only for the grate and brick-work of the combustion-chamber, but also the bed of the front flue, and carries with it the slide-valves I and J, but also becomes a part of the air-heating chamber and flue, as well as of the ash-pit. The division-plate or plates 27 (see fig. 6) are provided on both surfaces with connecting-flanges, recesses, collars, or any other mechanical arrangement. By means of this plate 27 one or more additional congeries of tubes can be attached, thus lengthening the flues as well as dividing them through that section, thereby adding as much more surface as desired to the action of the heat and the air, radiating the heat at a lower temperature, producing to a greater extent a breathable, healthy, and pleasant atmosphere, much more suitable for those having weak lungs than the heated air of ordinary furnaces, where the surface is less, and that surface very highly heated. These plates are also used in connection with cross-walls of brick-work, which form, as it were, a continuation of the division-plate 27, and serve as a division of the hot-air chamber, thereby giving more perfect control of the heated air, which by this means can be readily applied to certain parts of buildings not readily warmed when connected with a single air-chamber, as at all times the longer and larger distributing-pipes of hot-air furnaces take away, by the strong current, the heated air, producing a back action in the shorter and lesser pipes, thereby taking away entirely or lessening the effect desired at those points. In the cross-walls of brick-work, valves may be placed to connect the whole chamber if desired.

It will be seen that by such a combination I do not depart from my present invention, but only increase its utility and economy. The heating-apparatus which I have just described is not altered in any respect, the presence of the division-plate or plates and cross-walls of brick or other material serving to place the same more completely under the control of the operator, and allowing the heating air to be received either from the series of tubes upon one side of the division-plate or plates 27 or from the opposite series of tubes supplied with heating air from the combustion-chamber, in the precise manner described, in which no division-plate or plates was or were used.

Having thus described my present invention, what I claim as new, and desire to secure by Letters Patent, is—

1. I claim the combination of the grate E, ash-pit D, and combustion-chamber C, with the slide-valve I, for the purposes indicated.
2. I claim the slide-valve at the junction of the upper and under front flue, for the purposes described.
3. I claim the upper front flue covered externally with a non-conducting lining, as a portion of the combustion-chamber.
4. I claim the corrugated tubular externally-flanged chamber, provided with an incombustible termination, constructed and operating substantially as shown, for the purposes pointed out.
5. I claim a semi-cylindrical reverberating chamber of combustion, when combined with a flue and a series of tubes, for the purposes specified.
6. I claim a feeding-chamber in combination with an arched chamber of combustion and the abutments for properly distributing the fuel upon the grate.
7. I claim constructing the bed-plate or grate-plate in such a manner that the same shall form a support for the grate and brick-work of the chamber of combustion, as well as the bed of the front flue.
8. I claim the division-plate, in combination with a series of tubes, for the purposes fully described.

CHAS. J. SHEPARD.
